SELF-FEEDING CARBURETOR FOR INTERNAL-COMBUSTION ENGINES

**John N. Morris, Birmingham, England, assignor
to The S. U. Carburetter Company Limited,
Birmingham, England**

Application June 1, 1950, Serial No. 165,408
In Great Britain September 7, 1949

6 Claims. (Cl. 261—44)

1

This invention relates to self-feeding carburetors for internal combustion engines, and, more specifically, is concerned with carburetors of the kind in which the contents of the float chamber are subjected to the depression produced by a venturi or variable effective cross-sectional area which, together with a tapering needle controlling a main metering jet, is adjustable by pressure-responsive means movable in response to variation of the pressure drop established by the venturi.

A carburetor of the kind in question is disclosed in the specification of Patent No. 2,167,892. Its adjustable venturi is so designed as to afford at all times a substantially constant correlation between the depression existing immediately at the up-stream side of the engine throttle and that at some particular cross-section of the venturi, the depression available at that section being maintained substantially at the minimum value sufficient to raise liquid fuel from a tank situated at a lower level than the carburetor, without the aid of an extraneous fuel pump.

When employed in motor vehicles, the earlier form of carburetor referred to has been found to function very satisfactorily so long as the vehicle is not ascending a severe gradient. Upon such an ascent being undertaken, the carburetor operates with the drawback of a very adverse suction head, and this condition is, of course, worsened the longer the wheel base of the vehicle. Although continuity of fuel-feeding in that case could be achieved by so proportioning the factors involved that the carburetor always operated with an induction depression sufficiently great to cater for any contingency likely to arise, this expedient would cause some loss of engine power by unduly restricting the charge and would detract unacceptably from the efficiency of the carburetor under normal running conditions.

The drawback mentioned above is obviated by means of the present invention, which provides that whenever the float chamber level becomes abnormally low due to a change from the normal operating conditions rendering the depression in that chamber no longer sufficient to lift the fuel, a normally inactive emergency control device becomes effective to diminish progressively the ratio of the depression acting upon the pressure-responsive means to that obtaining in the venturi, with the result that the pressure-responsive means initiates a reduction of the effective cross-sectional area of the venturi, with consequent increase in the depression therein and in the float chamber sufficient to recommence inspiration of

2

fuel, whereupon the emergency control device becomes arrested in its obstructive action. To this end, a carburetor in accordance with the present invention comprises a suction chamber containing a loosely fitting piston having a co-axial nose-piece of varying cross-section which extends from the inlet to beyond the throat of the venturi and is so contoured as to afford a normal Venturi action for all degrees of entry, and a valve-like member which, whenever the fuel level in the float chamber becomes abnormally low, is moved by float-actuated means to obstruct progressively the normal flow of air which takes place from atmosphere, by way of the clearance around the piston, through the suction chamber and thence to an outlet at or near the throat of the venturi, whereby the momentarily diminished suction exerted on the piston results in the nose-piece reducing the effective cross-sectional area of the venturi until the depression in the float chamber increases to a value sufficient to recommence inspiration of the fuel, and the float-actuated means, together with the valve-like member operated thereby, becomes arrested in its action.

25. Although the emergency control device or valve-like member referred to may take various forms, it is preferred to employ a poppet valve which is disposed vertically with its stem depending above a lever operable by the float, the head of the valve lying opposite, and normally remote from, the outlet end of a passage by which the suction chamber is placed in communication with the outlet at or near the throat of the venturi.

According to a further feature of the invention, the pressure-drop constituting the metering head is derived by affording the float chamber restricted communication with atmosphere through an air jet of small bore so arranged with respect to an outlet duct that the air stream induced through the bore is compelled to suffer a reversal of direction before it can escape through the outlet duct to an outlet at or near the throat of the venturi.

The accompanying drawing represents, in somewhat diagrammatical form, a central vertical section through a self-feeding down-draught carburetor arranged in accordance with the invention.

The carburetor illustrated has a cylindrical suction chamber 1 the lower portion of which is formed with a set of peripheral ports 2 (only one of which is shown) open to the atmosphere. Air entering through these ports has free access to a region 3 at the inlet end of a venturi 4 which, adjacent its outlet end, is fitted with the usual

butterfly throttle 5. A flange 6 is provided for bolting the carburetor to the inlet manifold of the engine.

The suction chamber 1 contains a loosely fitting piston 7 which, together with a depending co-axial nose-piece 8, is slideable on a centrally disposed hollow guide 9, fixed to the upper part of the suction chamber 1, and is biased downwardly by a helical compression spring 10 of low rate. The nose-piece 8 is so shaped that it regulates the effective cross-sectional area of the venturi 4 in accordance with the instantaneous position of the piston 7. In this connection, since the multiplying effect of a venturi is determined by the rate of change of cross-sectional area along its axis, the profiles of the overlapping portion of the venturi 4 and the nose-piece 8 need to be such that, whatever the axial position of the nose-piece within its range of travel, the difference between the squares of their diameters at every axial position diminishes progressively towards the point at which the effective cross-sectional area of the venturi 4, that is to say the cross-sectional area of the annular gap between the venturi and the nose-piece, is required to be a minimum. The construction in question, therefore, affords an annular venturi of variable flow capacity in which the maximum air velocity (and hence the minimum pressure-head) always occurs at one particular cross-section. This is at the throat of the venturi, where there is an annular slot 11 through which the metered fuel is delivered and which will be designated the "low-pressure annulus."

The weight of the piston and nose-piece unit, augmented by the action of the spring 10, tends to cause the Venturi passage to be closed by the nose-piece 8. This tendency, however, is opposed by the depression existing in the upper part of the suction chamber 1 whenever the carburetor is functioning. The depression referred to, which acts upon the upper face of the piston 7, is derived from the low-pressure annulus 11 by way of a duct 12 and a passage 13. The space above the hollow guide 9, which is sealed from atmosphere by means of a screw-cap 14, is also permanently in communication with the low-pressure annulus 11 through a duct 15 which communicates with the passage 13.

So long as the engine is running, the carburetor automatically raises liquid fuel from a tank located at a lower level without the aid of a fuel pump. The fuel, which enters through an inlet 16 fitted with a cylindrical gauze filter 17, passes into a reservoir 18 and thence through a duct 19 to the seating of a needle valve 20 which, in the usual manner, is controlled by a pivoted float 21 in a float chamber 22, the fuel being supplied to the latter through orifices 23 whenever the needle valve is open. From the float chamber, the fuel passes by way of a duct 24 to a jet chamber 25 having a main jet 26 the effective aperture of which is controlled by a tapered metering needle 27 carried by the piston 7. The upper end of the needle 27 is held permanently in contact with the base of the piston 7 by means of a spring clip 28 which is anchored in a groove 29 formed at the junction between the piston and its nose-piece. The needle is mounted so that it has radial freedom of movement 70 with respect to the piston and nose-piece unit, and is centralised in the jet 26 by a guide-bore 30.

When the carburetor is in operation, air entering through the ports 2 is drawn from the at-

mospheric region 3 downwards through the annular passage between the venturi 4 and the nose-piece 8. Some degree of depression will thus prevail throughout this passage which, owing to its Venturi form, will be progressively greater as the cross-section of the passage diminishes. Maximum depression will, of course, occur at the low-pressure annulus 11 and the minimum in the neighbourhood of the throttle 5. Maximum value of the ratio between these two degrees of depression has been sought in developing the Venturi and nose-piece forms, and a ratio of approximately 4:1 has been found attainable. Thus, by choosing a value of piston 15 weight and spring strength which ensures a depression of 40 ins. water head at the low-pressure annulus 11, a depression of only 10 ins. water head results in the neighbourhood of the throttle 5 and, therefore, throughout the induction tract, under all full-throttle conditions. This figure is maintained at a substantially constant value provided the carburetor is of adequate size for the engine, that is to say, provided the piston and nose-piece unit only attains maximum lift when the engine breathing demand is at its absolute maximum.

The degree of depression existing in the low-pressure annulus 11 also has access to the upper side of the piston 7 via the duct 12 and passage 13. Since the majority of the lower surface of the piston lies within the atmospheric region 3, an upward pneumatic load is exerted upon the piston and nose-piece unit, which, in consequence, rises until the upward force becomes balanced by the combination of the weight of that unit and the load of the spring 10. When this condition of balance is achieved the piston and nose-piece unit will have attained a condition of stability, with the piston 7 sufficiently lifted and, therefore, with the nose-piece 8 sufficiently withdrawn from the venturi 4 to ensure that the resultant effective cross-sectional area of the annular venturi is such as to produce exactly the required degree of depression. Since the downward force represented by the weight of the piston and nose-piece and the spring load remains substantially constant, it is clear that the degree of depression effective upon the upper face of the piston 7 must also be substantially constant throughout the normal range of operation.

As the piston assembly rises the metering needle 27 is also progressively withdrawn from the main jet 26. The contour of the effective part of the needle can, of course, be so chosen as to give any required fuel/air ratio corresponding to any degree of piston lift and, therefore, of air flow to the engine. Fuel drawn from the float chamber 22, having been metered on passing the main jet 26, flows upwards within a well 31 and enters the low-pressure annulus 11 from the annular slot of which it issues, mixing with the air at this region of minimum pressure and, therefore, maximum velocity. Exceptionally good pulverisation of the fuel is consequently achieved.

Instead of the upper part of the float chamber 22 being freely vented to atmosphere (as is the normal practice), it is placed in communication with the low-pressure annulus 11 by way of ducts 32 and 33 and the duct 12. It is, however, afforded restricted communication with atmosphere through an air jet 34 of small bore which permits a slight amount of air to be drawn into the duct 32 under the influence of the sub-atmospheric pressure prevailing in the low-pressure

annulus 11 and, therefore, in the float chamber 22. Since the arrangement is such that the stream of air induced through the jet 34 can only leave the duct 32 by proceeding through the duct 33 (there being no other air outlet from the float chamber), the air stream in question has to suffer a reversal of direction within the duct 32 in order to enter the duct 33 from which it passes, by way of the duct 12 and the low-pressure annulus 11, into the main air stream in the 10 venturi 4. In consequence a finite difference of static pressure is established between the ends of the duct 32, and hence between the float chamber 22 and the low-pressure annulus 11. This pressure-drop, which is maintained across 15 the main jet 26, constitutes the metering head. Its magnitude is a function of the dimensions of the jet 34 and the duct 32, and it can be consistently kept without difficulty at a value equivalent to approximately 5 ins. water head. This 20 metering head is also made available for an enrichment or cold-starting jet 35 which is connected to the float chamber 22 by a passage 36 and supplies additional fuel to the low-pressure annulus 11 by way of a duct 37 when, by 25 rotation of a mixture control lever 38, the end of a projection 39 formed on a screw-threaded shank 40 is withdrawn from the facing containing the enrichment jet 35. Although not indicated in the drawing, a linkage is provided 30 between the mixture control lever 38 and the throttle 5 to effect partial opening of the throttle when the enrichment jet 35 is brought into use by a manual control.

So long as normal operating conditions prevail, a small poppet valve 41 remains inoperative in the position shown, its head being sufficiently remote from the bottom of the passage 13 to afford no obstruction thereto. If, however, under conditions of exceptionally high 40 fuel-lift (such as may arise due to a combination of severe gradient and long wheel base), the fuel-lift called for exceeds the depression available in the float chamber, the fuel flow begins to diminish and the float 21 drops. In dropping, the float at first opens the needle valve 20 to its 45 fullest extent and then, by means of an associated lever 42, begins to raise the valve 41 so that the normally free communication provided by the passage 13 becomes partially obstructed. As this 50 obstruction occurs, the small flow of air which inevitably takes place from atmosphere in the interior of the suction chamber 1 through the clearance provided between the suction chamber and the piston 7, can now no longer be freely evacuated via the passages 13 and 12. The 55 degree of depression in the suction chamber therefore commences to drop below its normal value, with the result that the piston 7 sinks somewhat and the nose-piece 8 enters the venturi to a greater extent than normal. The additional 60 obstruction thereby imposed upon flow through the venturi then results in an increment in the depression normally obtaining in the low-pressure annulus 11 and hence in the float chamber 22. This effect is progressively intensified as the head of the valve 41 continues to 65 approach the outlet of the passage 13, until the increased depression in the float chamber reaches a value sufficient to recommend the inspiration of fuel.

When fuel commences to flow again into the float chamber the raising of the float permits the valve 41 to descend, and consequently the 70 restricting influence of this valve diminishes

until the float chamber depression produced is just sufficient to maintain the required flow of fuel from the tank.

It will be appreciated that so long as an abnormally high fuel-lift continues, a condition of stability will be maintained, the action of the valve 41 performing the function of maintaining a substantially constant float chamber level in a manner analogous to that in which the needle valve 20 serves under normal conditions.

Only slight influences are exercised upon the general quality of the carburation when the carburetor is operating under these abnormal, or high-lift conditions. Thus the mixture ratios tend to become slightly richer due to the higher velocity of flow through the venturi 4, but simultaneously a slight weakening effect results from the abnormally low float chamber level. At the same time a temporary increase in depression at the Venturi throat implies a corresponding increase in the unmultiplied depression in the region of the throttle, which may thereby increase from the normal value of 10 ins. water head to, say, 11 ins. or 12 ins. The adverse effect of an increment in induction depression of this order upon power output is, of course, slight. Nevertheless, it is considered preferable to arrange for the carburetor to operate normally upon the lower manifold depression figure and to bring into operation the emergency high-lift mechanism to meet exceptional conditions only, rather than to operate, at all times, with sufficiently high depression throughout the system to meet circumstances which rarely occur.

Fluttering of the piston assembly is prevented by hydraulic damping. This is effected by retaining a quantity of light oil 43 in the bore of the nose-piece 8 and the lower part of the guide 9, the end of which is closed except for a small orifice 44, and providing a loosely fitting cylindrical baffle 45 within the guide 9. Thus, movement of the piston assembly cannot take place without corresponding displacement of the oil and the steady-ing effect which this engenders. The momentary high pressure created in the oil beneath the end of the guide 9, upon sudden upward movement of the piston assembly, may result in some oil being forced upwardly in the working clearance between the periphery of the guide 9 and the surrounding portion of the bore of the nose-piece 8. Any oil so displaced is received in the space between the guide 9 and an inner annulus 46 provided on the piston 7, and eventually returns to the interior of the guide 9 through a small hole 47.

Although the contour of the metering needle 27 is initially so chosen as to afford the most appropriate mixture ratios throughout the working range, provision is made for the mixture ratio under idling conditions, when the main jet is almost wholly obstructed by the needle, to be readily adjustable. To this end, the portion of the piston 7 against which the head of the needle 27 is 60 spring-loaded, as already described, is formed as a circular ramp 48 the face of which has a series of uniformly spaced small protuberances (not shown) the intervals between these defining the successive positions of adjustment. Thus, by 65 manually rotating the piston 7 the head of the needle 27 is caused to override the protuberances and click into the desired location, the degree to which the needle enters the main jet 26 for any given position of the piston 7 being determined by the direction in which the piston is rotated.

It should, perhaps, be mentioned here that when the piston and nose-piece unit assumes its lowest position it is arrested by the engagement of the lower face of the piston with an annular rib 49.

The carburetor incorporates an acceleration pump which automatically produces a temporary enrichment of the mixture upon sudden opening of the throttle. This pump comprises a spring-loaded flexible diaphragm 50 mounted in a chamber 51 which is filled with liquid fuel and is in open communication with an injector tube 52. The latter is associated with the flared mouth of the duct 24.

In the condition illustrated, the diaphragm 50 is fully distended to the right by means of its spring 53, which is of sufficient strength to maintain it in this situation against the suction existing in the float chamber under normal steady running conditions. When, however, the throttle is suddenly opened a momentary increase in the normal depression occurs in all internal spaces communicating with the low-pressure annulus 11, due partly to the inability of the piston assembly to respond instantly to the increased air-flow demand by reason of its inertia, and partly to the damping which momentarily delays its upward movement. This momentary abnormal depression within the float chamber space is transmitted to the chamber 51, bounded by the accelerator pump diaphragm 50, via the injector tube 52 and a passage 54 which communicates with the top of the chamber 51. The strength of the diaphragm spring 53 is so chosen that under these conditions the diaphragm 50 will collapse inwards (as permitted by an air hole 55), displacing fuel from the chamber 51 and causing it to discharge rapidly from the injector tube 52. The resulting injector effect produced at the mouth of the duct 24 will cause a momentary increase of head within this duct, and thus give rise to a momentary increase in the discharge past the main jet 26.

Finally it may be mentioned that this carburetor is remarkably effective in suppressing induction roar. Its silencing capability is attributable to the extremely high velocity of air flow at the throat of the venturi, this velocity approaching sufficiently closely to that of sound (under the conditions of temperature and so forth prevailing there) to reduce induction tract noise 50 to such an extent that only the simplest form of air-silencer, sufficient to deal with the high-frequency components of the noise (such as constituted by the throttle-edge hiss), is required.

I claim:

1. A self-feeding carburetor comprising a fuel chamber having a float therein and a suction chamber, said suction chamber having an air inlet and a venturi serving as its outlet, said chamber containing a loosely fitting piston having a co-axial nose-piece of varying cross-section which extends from said air inlet to beyond the throat of the venturi and which is so contoured as to afford a normal Venturi action for all degrees of entry into said outlet, a suction passage system intersecting the throat of said venturi and connecting it to said suction chamber on the opposite side of the piston from the venturi and to said fuel chamber, through which system there is a normal flow of air drawn from the atmosphere by way of the clearance around the loosely fitting piston through the suction chamber and suction passage system to the venturi, and a valve member located in said suc-

tion passage system and means for transferring the movement of said float to said valve member after said float has fallen below a predetermined level so as to obstruct progressively said 5 normal flow of air whereby the momentarily diminished suction exerted on the piston results in movement of its nose-piece to reduce the effective cross-sectional area of the venturi and decrease the pressure therein, thereby decreasing the pressure in the suction passage system and causing inspiration of fuel thereinto.

2. A carburetor according to claim 1 in which said piston is exposed at its bottom to atmospheric pressure from said air inlet and is biased downwardly against such pressure by spring means bearing against its top.

3. A self-feeding carburetor according to claim 1 in which the valve-like member is a poppet valve disposed vertically with its stem depending above a lever operated by the float, the head of the valve lying in and controlling the movement of air through said suction passage system.

4. A carburetor according to claim 1 in which a pressure drop between said fuel chamber and Venturi throat is maintained by affording the fuel chamber restricted communication with the atmosphere through an air jet of small bore so arranged with respect to an outlet duct leading to said Venturi throat that the air drawn in through the jet is compelled to suffer a reversal of direction before it can escape through said outlet.

5. A carburetor according to claim 1 having a needle controlled fuel injection valve in a passageway between said fuel chamber and venturi, in which the movement of said piston controls the movement of a tapering needle in said fuel injection valve, the top of said needle being spring loaded into contact with a circular ramp provided on the bottom of the piston.

6. In a self-feeding carburetor having an air inlet and an outlet, a fuel chamber, a float in said fuel chamber, pressure responsive means in communication with said air inlet, a variable venturi in said outlet, a suction passage system to transfer the pressure at said venturi to said pressure responsive means and to said fuel chamber, means whereby said pressure responsive means controls the effective cross-sectional area of and consequently the pressure in said venturi, valve means in said suction passage system for restricting said transfer of pressure to reduce the ratio of the depression acting upon the pressure responsive means to that obtaining in the venturi so that said reduction in ratio initiates a reduction in said effective cross-sectional area, and a consequent decrease in the pressure in said venturi, at the pressure responsive means and in the fuel chamber, and means for transferring the movement of said float to said valve means after said float has fallen below a predetermined level.
